DESIGN FOR A MINIATURE BAR

Alexander Marks, Chicago, Ill.

Application May 14, 1934, Serial No. 51,778

Term of patent 3½ years

To all whom it may concern:

Be it known that I, Alexander Marks, a citizen of the United States, residing at Chicago, in the county of Cook, in the State of Illinois, have invented a new, original, and ornamental Design for Miniature Bars, of which the following is a specification, reference being had to the accompanying drawing forming part thereof.

In the drawing—

The figure is a perspective view of a miniature bar showing my new design.

I claim:—

The ornamental design for a miniature bar, as shown.

ALEXANDER MARKS.
